(57) **CLAIM**

The ornamental design for a combined desk clock and USB hub, as shown and described.

DESCRIPTION

FIG. 1 is a perspective view showing the front, top and left side of the desk clock/USB hub showing my new design.

FIG. 2 is a front view thereof.

FIG. 3 is a top view thereof.

FIG. 4 is a right side view thereof.

FIG. 5 is a left side view thereof.

FIG. 6 is a back view thereof; and,

FIG. 7 is a bottom top view thereof.

The broken lines in the drawings are for illustrative purposes only and form no part of the claimed design.
